F. W. SCHEPMAN

BILL FILE

Filed Sept. 13, 1922

F. W. Schepman Inventor

By C. Brown & Co. Attorney

UNITED STATES PATENT OFFICE.

FREDERICK WILLIAM SCHEPMAN, OF EVANSVILLE, INDIANA, ASSIGNOR OF ONE-HALF TO WILLIAM C. MENKE, OF EVANSVILLE, INDIANA.

BILL FILE.

Application filed September 13, 1922. Serial No. 588,064.

To all whom it may concern:

Be it known that I, FREDERICK WILLIAM SCHEPMAN, a citizen of the United States, residing at Evansville, in the county of Vanderburg and State of Indiana, have invented a new and useful Bill File, of which the following is a specification.

This invention relates to bill files of the type using pivotally mounted arched wires.

10 The primary object of the invention is to provide a file of this character which is springless and noiseless.

15 Another object of the invention is to provide simple and efficient means for simultaneously opening and closing the arched wires.

20 Another object is to provide a device of this character so constructed that a plurality of bill files may be controlled by one operating element.

25 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

30 In the accompanying drawings:—

Figure 1 represents a top plan view of the file constructed in accordance with this invention with the top of the gear-enclosing chamber removed, and with the arched wires shown in closed position.

Fig. 2 is a front elevation thereof with the wires in open position.

Fig. 3 is a detail sectional view taken on the line 3—3 of Fig. 1, and

Fig. 4 is a detail front elevation of one of the post-supporting flanges.

In the embodiment illustrated, the file constituting this invention is designed to be mounted on a back or base board (not shown) such as is ordinarily employed with files of this character. The file comprises a metal base plate 1 which may be nickel plated or finished in any desired manner, and which is to be secured to the base board by suitable fasteners. This plate 1 is provided along its upper rear edge with a slotted extension 2 to provide for its being suspended from a nail or other support. The

front edge of the plate 1 is cut out as shown 55 at 3 and one end thereof has a longitudinal extension 4 provided on its front edge with an upstanding apertured ear 5 for a purpose presently to be described.

The front edge of the plate 1 on opposite 60 sides of the cut-away portion 3 has upstanding right-angularly disposed flanges 6 and 7 which form abutments for base blocks 10 and 11 of T-shaped posts 8 and 9. These blocks 10 and 11 have screw-threaded sockets 65 in their outer faces to receive fastening screws 12 which pass through longitudinally extending slots 13 in the flanges 6 and 7. These slots 13 permit the posts to be adjusted toward or away from each other to 70 insure the close engagement therewith of the cooperating arched wires 14 and 15 which are rotatably mounted in the plate 1 at points spaced from and in transverse alignment with the posts 8 and 9. 75

These posts 8 and 9 are preferably made tubular and are provided at their upper ends on their inner sides with longitudinally extending tongues 8^a and 9^a against which the bills or free ends 16 of the rotatable 80 arched wires 14 and 15 are designed to engage when in closed position.

The lower ends of the arched wires 14 and 15 are rotatably mounted in the plate 1 and have toothed pinions 17 and 18 fixedly 85 secured thereto in any suitable manner which are designed to mesh with a rack bar 20, the ends 21 and 22 of which are offset and arranged in parallel planes. The teeth 23 of these ends are located on opposite side 90 edges thereof to mesh with the teeth of the heads 17 and 18 as is shown clearly in Fig. 1. One end of the bar 20 projects longitudinally beyond the plate 1 and overlies the end extension 4 thereof and is provided on its upper face with teeth 24 with which are designed to mesh a gear 26 fixed to a lever 25 which is fulcrumed in the upstanding apertured ear 5 of the extension 4. The gear 26 is provided on one face thereof with 95 a spacing disk 27 preferably integral with the gear and from the periphery of which extends radially the body portion or lever proper 28. This lever 28 is shown constructed of a metal bar with its outer end 100 twisted to form a flat finger grip 29 to facilitate the manipulation of the lever. A fiber washer 30 is shown arranged on the

outer face of the gear 26 of the lever and through which a screw 31 passes which performs the function of a fulcrum for the lever as well as securing element for attaching it to the ear 5. A lock nut 32 may be applied to the screw 31 to prevent its working loose.

From the above description it will be obvious that the pinions carried by the arched wires mesh with the rack bars 20 as shown and described and will operate when said bar is reciprocated longitudinally to open or close said wires. The upward swinging of the lever 25 operates to move the rack bar 15 outward as shown in Fig. 2 and to simultaneously turn the pinions 17 and 18 thereby swinging the arched wires 14 and 15 in opposite directions away from each other. The downward movement of this lever 25 causes 20 the rack bar 20 to move longitudinally inward thereby rotating the pinions 17 and 18 and swinging the wires 14 and 15 toward each other into closed position as shown in Fig. 1. When these wires are closed their 25 bills or terminals 16 abut the tongues 8^a and 9^a which limit their closing movement.

The rack bars 20 and the pinions 17 and 18 are enclosed by a removable casing 33 which is apertured for the passage of the 30 upstanding portion of the arched wires forming bearings for said wires and permitting them to turn freely in said casing.

It will thus be seen that this bill file has no springs to get broken or get out of order 35 and that the operation thereof is entirely noiseless.

Any suitable means may be provided for retaining the lever in raised or lowered position.

I claim:—

1. In a bill file, a base plate, a post rising therefrom and having a longitudinally extending tongue at its upper end, an arch member mounted to rotate on said plate with its free end adapted to engage said tongue when in closed position, a rack bar slideable on said base, a pinion carried by said arch member and meshing with said rack bar, a lever fulcrumed on said plate and having a gear meshing with said rack bar whereby the swinging of said lever will reciprocate said rack bar and open and close said arch member.

2. In a bill file, a base plate, a plurality of spaced posts rising therefrom and adjustable toward and away from each other, a plurality of cooperating arch members mounted to rotate on said plate and cooperate with said posts to close the file, pinions carried by said arch members, a longitudinally reciprocatory rack bar mounted on said plate with the ends thereof offset, said offset ends being provided one on its outer edge and the other on its inner edge with the teeth to mesh with said heads whereby the reciprocation of said bar will open and close said arch members, said rack bar having teeth on its upper face at one end thereof and a lever having a gear meshing with said teeth to reciprocate said bar.

In testimony that I claim the foregoing as my own, I have hereto affixed my signature in the presence of two witnesses.

FREDERICK WILLIAM SCHEPMAN.
